CLAIM

The ornamental design for a personal computer stand, as shown and described.

DESCRIPTION

FIG. 1 is a right side perspective view of a personal computer stand;

FIG. 2 is a left side reduced perspective view thereof;

FIG. 3 is a front elevational view thereof;

FIG. 4 is a back elevational view thereof;

FIG. 5 is a right side elevational view thereof;

FIG. 6 is a left side elevational view thereof; and,

FIG. 7 is a top plan view thereof.

The bottom view is plain and unornamented.

A personal computer is shown in broken lines in FIG. 2 for illustrative purposes only and forms no part of the claimed design.

FIG. 2

FIG. 3

FIG. 4

FIG. 5

FIG. 6
